PAGE 3

FIGURE 1 is a side elevational view of an offshore drilling vessel showing our new design;

FIGURE 2 is an enlarged fragmentary front elevational view thereof;

FIGURE 3 is an elevational view of the side opposite that shown in FIGURE 1;

FIGURE 4 is an enlarged fragmentary rear elevational view thereof;

FIGURE 5 is a top plan view thereof; and

FIGURE 6 is a bottom plan view thereof.

We claim:

The ornamental design for an offshore drilling vessel, as shown.
